UNITED STATES PATENT OFFICE.

GEORGE W. LONGSTAFF, OF BRIDGEPORT, CONNECTICUT.

DESIGN FOR A CABINET FOR SEWING-MACHINES.

SPECIFICATION forming part of Design No. 25,104, dated January 28, 1896.

Application filed December 26, 1895. Serial No. 573,422. Term of patent 7 years.

To all whom it may concern:

Be it known that I, GEORGE W. LONGSTAFF, a citizen of the United States, residing at Bridgeport, in the county of Fairfield and State of Connecticut, have invented and produced a new and original Design for Sewing-Machine Cabinets; and I do hereby declare the following to be a full, clear, and exact description of the invention, such as will enable others skilled in the art to which it appertains to make and use the same.

Referring to the accompanying drawings, Figures 1 and 2 are front and rear elevations, respectively, of the cabinet-case, showing my design; and Fig. 3 is an end elevation of the same.

The leading features of my design consist in the generally rectangular-shaped body portion whose sides are bounded at the lower edges by a plain concavo-convex curved line,

and the plain vertically-rising legs which extend from the table of the cabinet along the corners of the body portion, said legs being without the angles formed by the meeting sides of said body.

1 is the rectangular body, 2 the plain concavo-convex curved line, and 3 the vertical legs which extend from the table 4 down along the corners of the case and outside the same.

I claim—

The design for sewing-machine cabinets, substantially as shown in the accompanying drawings.

In testimony whereof I affix my signature in presence of two witnesses.

GEORGE W. LONGSTAFF.

Witnesses:

F. W. SMITH, Jr.,
M. T. LONGDEN.
